(57) **CLAIM**

The ornamental design for a security light, as shown and described.

DESCRIPTION

FIG. 1 is a top, front, right side perspective view of a security light showing our new design;
 FIG. 2 is a front elevation view thereof;
 FIG. 3 is a rear elevation view thereof;
 FIG. 4 is a right-side elevation view thereof;
 FIG. 5 is a left-side elevation view thereof;
 FIG. 6 is a top plan view thereof; and,
 FIG. 7 is a bottom plan view thereof.

The dashed broken lines in FIGS. 1-7 represent unclaimed parts of the design, and the dash-dot broken lines represent boundaries of the claimed design. All of the broken lines form no part of the claimed design.
